ATTORNEY.

UNITED STATES PATENT OFFICE

2,543,168

TOBACCO PIPE

David Russell Herriott, Glendale, Calif.

Application March 9, 1948, Serial No. 13,870

3 Claims. (Cl. 131—184)

1

The invention relates to a tobacco pipe and more particularly to a pipe having a cleaning device attached to the bit so that the bit can be operated to clean the device. The cleaning device is also of such a nature as to condense the tar from the smoke while the pipe is in use and while the bit and the cleaning device are stationary.

An object of the invention is to provide an improved device for cleaning the fluid in the stem and to permit its removal by blowing through the bit.

Another object of the invention is to provide a tobacco pipe having a blow-out opening controlled by a valve head on a movable bit, with means yieldingly retaining said valve head in position to close the blow-out opening, for smoking purposes.

Another object of the invention is to provide a bit which may be operated to clean or remove the heel at the juncture of the bowl with its stem or to ram and loosen the tobacco at that location so that the pipe will draw better.

Another object of the invention is to provide a mechanical filter for the smoke, the filter forming a permanent part of the pipe and not requiring replacement.

For further details of the invention reference may be made to the drawings wherein—

Fig. 1 is an enlarged vertical sectional view of a tobacco pipe according to the present invention, the bit and its attached cleaning device being shown in one position for smoking.

Fig. 2 is a sectional view like Fig. 1 with the operating parts in cleaning position.

Fig. 3 is a sectional view on line 3—3 of Fig. 1 looking in the direction of the arrows.

Fig. 4 is an enlarged sectional view on line 4—4 of Fig. 1 looking in the direction of the arrows.

Fig. 5 is a longitudinal sectional view of a modified construction.

Referring in detail to the drawings, the tobacco pipe 1 comprises a bowl 2 preferably of briar and having an integral short shank 3 having a threaded bore 4 which opens into the interior 5 of the bowl at its lower end. Threaded into the bore 4 is a metal coupling 6 having a central external diameter preferably the same as that of the shank 3 and having an aperture 7 for a spanner wrench so that it can be screwed in or out. The coupling 6 has a threaded extension 8 which fits into the bore 4 so that its end 9 is substantially flush with the wall 10 of the bowl, while the bore 11 which extends through the coupling

6, at its lower portion 12 is substantially flush with the bottom wall 13 of the bowl. The other end of coupling 6 has an extension 14 having threaded engagement 15 with a metal hollow stem 16. The coupling 6 has a shoulder 17 which abuts the end 18 of the shank 3 and also a shoulder 19 which abuts the end 20 of the stem 16. The stem 16 extends beyond the coupling 14, to provide a chamber 21. The end 22 of the stem extension 16 is inturned and provided with a bore 23 to slidably receive the rear end 24 of a cleaning device 25 of metal. All metal referred to above is preferably aluminum. The end 24 has a threaded nipple 26 to receive the threaded bore 27 in the bit or mouthpiece 28. The cleaning device 25 is therefore mounted on, carried by, and operated by the bit 28.

To prevent the bit 28 and cleaning device 25 from rotating, the end 24 has an enlarged circular head 29 which slidably fits in the bore of the chamber 21. The movement of the bit 28 and cleaning device 25 rearwardly is limited by the shoulder 30 on the head 29 striking the shoulder 31 on the inturned end 22. The head 29 is provided with a longitudinal slot 32 and the stem extension 16 is provided with a key 33 which rides in slot 32. As shown in Fig. 4, key 33 may comprise a sleeve 34 in threaded engagement 35 with the bore 36 through the wall of the stem 16. Sleeve 34 has an extended end 37 which rides in the slot 32. In the sleeve 34 is a spring 38 pressing on a ball 39 which rides on the bottom of the groove 32. Groove 32 has a recess 48 for the ball at the front of head 29, to frictionally hold the bit 28 and cleaning device 25 in the smoking position shown in Fig. 1.

The cleaning device 25 also comprises an integral elongated rod 40 which is smaller in diameter than the bore 11 of the coupling 6, to provide a smoke passage through bore 11. The front end 49 of rod 40 terminates in line with the bowl wall 10 when the device is in smoking position.

In the chamber 21, the cleaning device 25 has a disk valve head 41 which slidably fits in the cylindrical bore of chamber 21. Valve 41 has in its periphery a plurality of spaced ports like 42 and 43 which extend lengthwise of the axis of the stem extension 16. In the smoking position, the ports 42, 43 are open so as to pass the smoke from the bowl to the bit, and in this position an imperforate portion 44 of the valve 41 closes a drain outlet 45 at the lower portion of the stem extension 16 in front of the bit 28. The cleaning device 25 also has integral spaced

baffles 46 and 47 between the valve 41 and the head 29, these baffles being smaller in diameter than the bore of chamber 21.

The whole cleaning device 25, including rod 40, valve head 41, baffles 46, 47, head 29 and end 24 can be cast in one piece of aluminum, or machined from an aluminum rod. The smoke is cooled by contact with these parts and by contact with the inside of metal coupling 6 and stem extension 16.

The operation of the pipe in Figs. 1 to 4 is as follows:

When the parts are in smoking position as shown in Fig. 1, tar condenses from the smoke on the exterior of rod 40 and on the adjacent wall of the bore 11. The smoke proceeds through the ports 42, 43 and further condensation takes place on the baffles 46, 47. Some liquid accumulates in the lower portion of chamber 21 which serves as a well and the head 29 is provided with a smoke passage 50 which opens at its lower end above the well, this passage being inclined upwardly in a rearward direction, and extending through the bit as shown at 53 so that liquid in the bit or in the rear end 24 of the cleaning device will drain out of passage 50 into chamber 21.

The stem extension 16 is provided with an aperture 54 for a spanner wrench so that the stem extension can be removed from the coupling 6, this also permitting removal of the bit 28 and the cleaning device 25 carried thereby so that these parts can be inspected or cleaned, but this should be necessary very seldom. During the usual and normal operation of the pipe it is not necessary to take it apart as the smoke is cleaned and liquid is accumulated in the bottom of chamber 21 without any special operation and in the normal course of smoking.

If an accumulation of burnt tobacco remains at the bottom of the bowl adjacent the end 9 of the coupling, this can be loosened by pushing on bit 28 which projects the rod 40 forwardly so that its front end projects into the bowl as shown in Fig. 3. When it is desired to remove the liquid accumulated at the bottom of chamber 21, the bit 28 is pushed forwardly to the position shown in Fig. 2, whereby the valve head 41 strikes the end 52 of the coupling 6 which acts as a stop to limit such forward movement, the end 52 also acting as a valve seat to close the ports 42, 43. When the valve head 41 is in that position, the exhaust outlet 45 is open as shown in Fig. 2 and hence by blowing into the bit 28, whatever liquid has accumulated in the bottom of chamber 21 is blown out through outlet 45.

The rod 49 also acts as a ram to loosen up tobacco at the lower portion of the bowl at the entrance to the coupling 6 as both the rod 40 and the valve head 41 are integral and as both are mounted on and carried by the bit 28, operation of the bit 28 by pushing it in or out operates both the rod 49 and the valve head 41 at the same time.

As shown in Fig. 5, the bit 128 and its cleaning device 125 may be resiliently held in smoking position shown, by means of a helical compression spring 60 the rear end of which bears against the valve head 144, its forward end bearing against a shoulder 61 at the forward end of bore 62 in the coupling 66. The spring 60 is mounted in the bore 62 and retracts into it when the bit 128 is pushed in. The bit 128 and its cleaning device 125, similar to cleaning device 25 above described,

are guided for reciprocating non-rotary movement by a key 133 in the form of a screw through the wall of the stem extension 116, the inner end of screw 133 riding in a slot 132 in the head 129. The construction and operation of the pipe of Fig. 5 is otherwise the same as described in connection with Figs. 1 to 4.

It will be apparent that various modifications may be made in the invention without departing from the spirit of the following claims.

I claim:

1. In a smoking pipe, a hollow tubular stem having a drain outlet, a coupling in threaded engagement with the forward end of said stem, a cleaning device in said stem comprising a disk valve head movable to open or close said outlet, said valve head having peripheral ports closed by said coupling when said valve head is in position to open said outlet, and a bit on said cleaning device.
2. A smoking pipe having a bowl, stem and a bit, said pipe comprising means mounted on said stem for guiding said bit for reciprocating non-rotary movement within said stem, said stem provided with a well in front of said bit, said well having an outlet, a ram for said bowl on said bit, and a valve head on said ram for closing said outlet, whereby both said ram and said valve head are operated by reciprocating said bit.
3. A smoking pipe comprising a bowl, a stem comprising a valve seat and a well, a bit having a passage opening into said well and having a movable supporting connection with said stem, said stem having an outlet for said well, a ram on said bit, a valve head on said ram, said valve head having a valve portion controlling said outlet and also having a valve face adapted to seat on said valve seat when said outlet is open, said valve head having a port opening into said valve face, said valve head being movable on movement of said bit when said stem is mounted on the bowl to either a position (a) shutting off communication between said well and said bowl and opening said outlet whereby the fluid contents of said well may be exhausted through said outlet by blowing through said bit, or a position (b) closing said outlet with said bit in communication with said bowl by way of said well and said port, and spring means associated with said bit for yieldingly retaining said bit in said last mentioned position.

DAVID RUSSELL HERRIOTT.
